FACE PLATE FOR A TRAFFIC CONTROL LIGHT

Christian J. Reimuller, Cherry Valley, Calif., assignor of
one-third each to Barbara J. Reimuller and Christian
Alan Reimuller, both of Cherry Valley, Calif.

Filed Mar. 6, 1967, Ser. No. 6,058

Term of patent 14 years

Int. Cl. D29—99

U.S. Cl. D72—1

The figure is a plan view of a face plate for a traffic control light embodying my new design, it being understood that the face plate has no substantial depth and that the opposite side is a plain flat surface.

I claim:

The ornamental design for a face plate for a traffic control light, as shown and described.
